BY HIS ATT'Y.

UNITED STATES PATENT OFFICE.

SAMUEL AYRES, OF WORCESTER, MASSACHUSETTS.

STOVE-PIPE SHELF.

SPECIFICATION forming part of Letters Patent No. 234,452, dated November 16, 1880.

Application filed May 21, 1880. (No model.)

To all whom it may concern:

Be it known that I, SAMUEL AYRES, of Worcester, Massachusetts, have invented a new and useful Stove-Pipe Shelf and Towel-Rack Combined, of which the following is a specification.

My invention relates to that class of shelves which are adapted to grasp the stove-pipe, and are held in place by that means. Its nature is fully shown by the following description and accompanying drawings of a combined stove-pipe shelf and towel-rack embodying my invention.

In said drawings Figure 1 is a perspective view, and Fig. 2 shows a plan, the same letters indicating the same parts in both.

To construct my invention I make a strong frame of pretty stiff wire, consisting of two partial rings, B and E, connected by short stays of the same. To the ends of this frame are attached the two grasping-loops D D, so constructed as to swing on the ends of the frame to admit of being put onto the pipe, and with their adjacent ends formed into eyes to receive the bolt C, by which the whole is held in place. To the frame B E, I connect the shelf, formed by the horizontal bars a a a a making the platform, their ends being turned one around the piece E and the other around A, or otherwise securely fastened, the outer edge of the platform being supported by the braces b b b firmly secured to A and B. The piece A is extended back beyond the shelf, as at A' A', and, with the bars F F, forms the towel-rack,

whose ends are supported by the braces b b, 35 similarly to the shelf.

By removing the bolt C the loops D D can be thrown apart and the whole be removed or put on the pipe, the bolt and its nut holding it when on, the peculiar construction of 40 the supporting-frame B E giving the greatest strength for the weight of material, and obviating the danger of a collapse of the pipe when old—or, in other words, the bending or breaking it by one or more of the braces b b 45 when a heavy article is placed on the shelf, as is liable to occur with the light metal bands which have heretofore been used for that purpose. The rack extending back allows the articles on it to hang clear of the stove. 50

I am aware that towel-racks and stove-pipe shelves adapted to be connected to the stove-pipe by means of circular loops and screw-bolts are not new, and I do not therefore desire to claim such a construction broadly; but 55

What I do claim as new and useful is—

As an improved article of manufacture, the herein-described stove-pipe shelf and towel-rack combined, consisting of the frames B E, having loops D D and screw-bolt C, and provided with the braces b, platform A a, and rack A' F, the whole being formed of wire rods, substantially as and for the purpose specified. 60

SAML. AYRES.
